UNITED STATES PATENT OFFICE.

LEROY J. TAYLOR, OF CHICAGO, ILLINOIS, ASSIGNOR TO LIBBY, McNEILL & LIBBY, OF CHICAGO, ILLINOIS, A CORPORATION OF MAINE.

DESIGN FOR A BOTTLE OR JAR.

53,694.

Specification for Design.

Patented Aug. 5, 1919.

Application filed April 18, 1919. Serial No. 291,145. Term of patent 14 years.

To all whom it may concern:

Be it known that I, LEROY J. TAYLOR, a citizen of the United States, residing at Chicago, in the county of Cook and State of Illinois, have invented a new, original, and ornamental Design for Bottles or Jars, of which the following is a specification, reference being had to the accompanying drawing, forming part thereof.

The figure is an elevation of the bottle or jar showing my new design.

I claim:

The ornamental design for a bottle or jar, as shown.

LEROY J. TAYLOR.
